UNITED STATES PATENT OFFICE

153,529

DESIGN FOR A BATHTUB

Leonard Keller, Tuckahoe, N. Y., assignor to
Borg-Warner Corporation, Chicago, Ill., a cor-
poration of Illinois

Application May 17, 1947, Serial No. 139,100

Term of patent 7 years

(Cl. D4—4)

To all whom it may concern:

Be it known that I, Leonard Keller, a citizen of the United States of America and resident of Tuckahoe, in the county of Westchester and State of New York, have invented a certain new, original, and ornamental Design for a Bathtub, of which the following is a specification, reference being made to the accompanying drawing, forming a part thereof, in which:

Fig. 1 is a front elevation of a bathtub, showing my new design;

Fig. 2 is a plan view thereof; and

Fig. 3 is a vertical section taken along the plane of line 3—3 on Fig. 1.

Fig. 4 is a perspective view taken slightly to one side of Fig. 2.

I claim:

The ornamental design for a bathtub, as shown.
LEONARD KELLER.
